Inventor, No. 13, of Jamestown, a New York.

Letters Patent.

The schedule referred to in these Letters Patent and making part of the same containing a description in the words of the said Thomas M. Harvey himself of his improvement in the manufacture of a nail or spike, designated the grooved and flanchon spike.

To all whom it may concern.

Be it known that I, Thomas M. Harvey, of Jamestown Chautauque County in the State of New York, have invented a new manufacture of Nail or Spike, which I designate, the grooved and flanchon Spike, to be used in the fixing of rails, and chairs in the construction of Rail roads, and for other purposes where it is desirable to attach articles by nailing more firmly than it can be done by nails or spikes of the ordinary construction, and I do hereby declare the following is a full and exact description of the construction of, or form given to, such nail or spike.

When these spikes are to be used for plate rails on rail roads, or for other similar purpose, the head and neck of the spike, for thickness of the nail, is made in the usual form, but the remainder of the shank or stem of the spike from the neck to the point, or until the point of projection, is grooved on two sides in such a way as to leave four projecting flanches, or fillets between one along each edge.

The section of the spike in the grooved part of the stem will then appear somewhat in the form shown in Fig. 3 in the accompanying Drawing, Fig. 1 & 2, represent two variations in the slope given to the lower part of the groove, which however may be indefinitely modified, without changing the principle. Fig. 3 in each figure, shows the grooved, & Fig. 3. the plain side of the spike; the dotted lines in the latter representing the manner in which the bottom of the groove may be rounded or inverted, for the purpose of causing it to hold the more firmly in the wood. See

1153A

which it is necessary to provide any machinery by which such rods and
spikes may be driven into which there is of any construction, and
for which I claim as a Patent on the 2d day of January A.D. 1832,
that they may be made by any adequate implements or machinery.

That I claim as my invention, is, giving a conical to each
or spike by growing them on their sides, so as to form flanks or
fins on their angles; whether this grows be made of equal depth
through its whole length or whether the bottom thereof be undulating
smaller, or elevated in the manner herein described, or made of
iron, copper, or other metal, or varied in any way which does not
essentially change the principle or manner of construction.

Witness,
